METHOD AND MEANS OF IDENTIFYING FABRICS

Application filed June 28, 1930. Serial No. 464,533.

This invention relates to improvements in identification devices, and has particular reference to a method and means of identifying textile fabrics and the like.

5 It is common knowledge that unscrupulous manufacturers and dealers in fabrics make a practice of imitating the quality and design of the products of others with intent to undersell the latter and defraud the public.

10 In accordance with the present invention it is proposed to remove the possibilities of deception of the above character by providing a means of identification for a fabric which will enable the purchaser thereof to 15 determine whether it is the product of the supposed vendor.

A feature of the invention is to cut a length 20 of fabric to form a strip which, after said length has been wound upon a roll, is secured to the latter by means of a seal which may bear certain identifying data, the strip being so secured that inspection and comparison thereof with the roll of fabric may be accomplished and the seal being such that if broken 25 or replaced the prospective purchaser will be warned of the lack of genuineness of the product.

The inventive idea involved is capable of receiving a variety of expressions, some of 30 which, for purposes of illustration, are shown in the accompanying drawings.

In the drawings—

Figure 1 is a fragmentary plan view of one 35 step in the method of mounting the same upon a roll;

Figure 2 is a longitudinal section through the roll of fabric in its complete form;

Figure 3 is a perspective view of one end 40 of the completed roll; and

Figure 4 is a similar view of a slightly different form of the invention.

The customary manner of preparing textile fabrics for shipment and distribution is 45 to wind a length of fabric on a support which is usually in the form of a cylinder made of any suitable material, or it may be a flat piece. The cylindrical form is preferable since it facilitates the examination of a fabric before distribution, this being accomplished

by inspecting the length of fabric as it is run through a machine and wound upon a roll which is longer than the width of the fabric so that the ends of the roll will project beyond the edges of said fabric. In this description and the appended claims the term "roll" is to be construed as covering any form of support upon which the fabric is wound.

The invention is shown in Figures 1 to 3 in its preferred form, wherein the length of fabric 5 is wound upon a roll 6. Preparatory to winding the fabric upon the roll and inspecting the same during the winding operation, the operator cuts the fabric lengthwise along the selvage thereof for a short distance, as indicated at 7 in Figure 1, to form a strip 8, which preferably is not wholly detached from the goods, although it is within the scope of the invention that the strip may be completely severed. Following this operation, the cut end of the fabric is adjustable upon the roll 6 with the ends of the latter projecting beyond the edges of the fabric. The strip 8 is then extended laterally from the selvage, as indicated in dotted lines in Figure 1, and the machine is started so as to wind the fabric upon the roll 6 during which the inspection of the goods takes place.

After the length of fabric has been completely wound upon the roll and removed from the machine, the strip 8 is adjusted so as to extend longitudinally of the exposed portion of the roll 6 and over the end thereof. In case the strip 8 should have been completely detached from the length of fabric, it would then be laid upon the surface of the roll 6 before the winding operation starts so that the inner end of said strip would be covered and held in position by the layers of the fabric as the latter is wound upon the roll.

The strip 8 is now secured to the roll 6 by means of a seal 9, preferably made from a flexible strip of material and adhesively applied to the roll circumferentially thereof with the intermediate portion of the seal extending over the part of the strip 8 which is disposed between the extremity of the roll and the edge of the fabric thereon, and the ends of said seal being attached to the surface

of the roll. The outer surface of the seal 9 may have any suitable identifying data thereon, such as the name of the manufacturer and other information which identifies the product as genuine. If so desired, another identifying label 10 may be secured to the loose extremity of the strip 8. Thus, a prospective purchaser may compare the strip 8 with the roll of fabric and also by noting the indicia on the seal 9 and the fact that it is intact, he will have reasonable assurances that the product is that of the manufacturer indicated on the seal and is genuine.

In Figure 4, the roll is shown as provided with a pair of spaced slits 11 extending circumferentially and of a length to permit of the strip 8 being inserted therethrough. After this has been done, a metal seal 12 is attached to the free end of the strip in any preferred manner, this seal being of such thickness that it cannot be drawn through the slits 11 without disrupting the latter, breaking the seal, or tearing the fabric. In either event, the surreptitious handling of the roll could be detected, thereby giving warning as to the originality of the goods.

What is claimed is:

1. In an identifying device for fabrics, the combination with a roll, and a length of fabric wound thereon with an edge spaced from one end of said roll to expose a portion of the latter; of a strip of said length partially detached therefrom and extended over the exposed portion of said roll, and a seal securing said strip to said exposed portion and extending over said strip.

2. In an identifying device for fabrics, the combination with a roll, and a length of fabric wound thereon with an edge spaced from one end of said roll to expose a portion of the latter; of a strip of said length partially detached therefrom and extended over the exposed portion of said roll, and a sealing strip attached to said exposed portion circumferentially thereof and covering a part of said strip of fabric.

In testimony whereof I have affixed my signature.

ERNEST C. GEIER.
